2 SHEETS—SET 2.

UNITED STATES PATENT OFFICE.

ERNEST NIEHOFF, OF BROOKLYN, NEW YORK

PROJECTILE.

No. 820,818.

Specification of Letters Patent.

Patented May 15, 1906.

Application filed November 16, 1904. Serial No. 232,859.

To all whom it may concern:

Be it known that I, ERNEST NIEHOFF, a citizen of the United States, residing at Brooklyn, New York, have invented certain new and useful Improvements in Projectiles; and I do hereby declare the following to be a full, clear, and exact description of the invention, such as will enable others skilled in the art to which it appertains to make and use the same.

My invention relates to projectiles for use in marine warfare, and more particularly to means for automatically igniting explosive contained therein upon the submersion thereof at a predetermined depth.

As is well known, shells, torpedoes, and other projectiles after being projected by firing means are exploded automatically in one of several ways, such as by means of time-fuses, percussion-fuses, &c. The last-mentioned igniting means, which is most generally used, is dependent for its action solely upon the contact by the shell with the resisting-surface of the object at which it is fired. Upon contacting with said object the shell or other projectile is exploded; but in the event of the device going wide of its mark the same will sink below the surface of the water without exploding, or if the projectile is in the form of a float, such as the ordinary torpedo, it will drift upon the water and become a menace to shipping.

The object of my invention is to provide a projectile having means whereby the same will be exploded automatically should it sink subsequent to its forward movement to a predetermined level below the surface of the water.

A further object is to employ means whereby a floating projectile will not only explode automatically after reaching a predetermined level below the surface of the water, but will be caused to lose its buoyancy after its forward movement has ceased.

With the above and other objects in view it consists in certain novel constructions, combinations, and arrangements of parts, as will be hereinafter fully described, and pointed out in the claims.

In the following drawings I have shown my improvements applied to an explosive shell and to a torpedo; but it will of course be understood that, if desired, a mine or any other form of explosive device may be provided with my invention.

In the drawings, Figure 1 is a central longitudinal section through a shell having a percussion-fuse, said shell being provided with my improved igniting mechanism. Fig. 2 is an enlarged transverse section through the shield of the mechanism and the adjoining portion of the shell. Fig. 3 is a conventional showing of a longitudinal section through a "Whitehead" torpedo having my improved mechanism applied to it, and Fig. 4 is a central longitudinal section through a modified form of shell adapted to be exploded solely by means of my invention.

Referring to the drawings by numerals, 1 is a body or shell having any suitably-shaped compartment 2 therein, which may be located at the center or at any other suitable point. Communication with this compartment may be had through an opening 3, in which is normally arranged a screw-cap 4. Any suitable means may be employed for removing this cap. It will be understood, however, that the outer surface thereof must remain normally flush with the outer surface of the shell. A passage 5 extends through the cap 4 and is normally closed at its outer end by the valve 6, the stem 7 of which extends through the passage and has a head at its inner end. A spring 9 is interposed between this head and the cap for the purpose of holding the valve 6 normally seated upon the end of the passage. It will be seen that a valve of this construction will open only when pressure is exerted thereon from the interior of compartment 2, and any pressure upon the outside of the shell will tend to force the valve more firmly upon its seat.

Formed within the wall of shell 1 at a point preferably diametrically opposite the cap 4 is a recess 10, having longitudinally-extending grooves 11 formed in the inner wall thereof at its sides, and these grooves are adapted to receive wings 12, which extend at right angles from the side edges of a shield 13, which is adapted to fit snugly within the recess 10 and with its outer face flush with the outer surface of the shell. The forward end of the shield 13 is hinged to the shell, as shown at 14, and a spring 15 is seated within a recess 16, formed in the shell, and is adapted to bear upon the other end of shield 13.

An inlet-opening 17 is formed within the wall of the shell at a point preferably adjacent the center of recess 10, and this opening communicates with the interior of a perfo-

rated valve-casing 18, which is secured within the compartment 2 and surrounds the inner end of inlet 17. A slide-valve 19 is mounted in the casing 18 and is held normally seated upon the inner end of inlet 17 by means of a spring 20, which is interposed between said valve and the inner end of its casing. It will be understood that when the valve is in its normal position communication between the inlet 17 and the apertures in the valve-casing 18 are cut off. A suitable receptacle, such as a hollow ball of wire-netting 21, is secured upon the inner end of casing 18 at a point preferably in the center of compartment 2, and this receptacle is adapted to contain a "water-primer," consisting of any one of several chemicals, which ignites when water is applied thereto. Among these chemicals may be mentioned sodium (Na), potassium (K), and strontium (Sr). Extending from the receptacle 21 is a tube 22, which projects through the wall of compartment 2 and contains a combustible fuse 23, the inner end of which contacts with the chemical referred to, while the opposite end is exposed to and adapted to explode the charge 24 in the shell.

In using the projectile herein described the same is inserted into the barrel of the cannon or other projecting device employed, and it is obvious that when in this position the shield 13 will be depressed into its recess 10 and its outer surface held flush with the adjoining face of the shell. The inlet 17 is thus effectively sealed against the admission of any sparks or external pressure, and the projectile can be expelled from the barrel in any ordinary manner without danger of the explosion of its contents from any accidental cause. Immediately upon leaving the projecting device the hinged shield is pressed outward by the spring 15, as shown by dotted lines in the drawings. After the projectile strikes a body of water and during its progress therethrough or thereover the igniting mechanism remains unaffected thereby, for the reason that the outwardly-projecting shield 13 and its wings 12 serve to deflect the water as the projectile goes forward and preventing it from entering between said shield and the wall of the shell and into the inlet 17. After the forward movement of the projectile has ceased, however, the water is free to enter between the shield and shell, and as the device sinks the water-pressure will obviously increase. When this pressure reaches a predetermined degree, the resistance offered by spring 20 will be overcome and valve 19 will be moved inwardly, thereby exposing one or more of the openings in the casing 18. Water is thus free to flow into compartment 2, and the air displaced thereby will pass outward through the valved opening 5 in cap 4. As the water enters the compartment 2 the level thereof will gradually rise

until it comes in contact with the receptacle 21 and its contents. The chemical action of the water upon this material, whether the same be sodium, potassium, or strontium, will cause ignition of the fuse 23, and the explosive charge 24 will thus be ignited and cause the explosion of the projectile. By employing a substantially spherical compartment 2 the same period will be necessary for the water to rise to the chemical at the center of said compartment no matter what position the projectile may assume within the water. By removing the cap 4 access may be readily had to the compartment 2 for the purpose of removing or replacing the receptacle 21 and its contents. It will of course be understood that the explosion of the projectile herein described is not dependent solely upon the sinking thereof, for, as shown in the drawings, the said projectile may be provided with a percussion-fuse, so as to cause it to explode upon contacting with a solid object. My improvements hereinbefore described are solely for the purpose of insuring the explosion of a projectile whether or not it is fired.

In Fig. 3 I have shown the ordinary type of Whitehead torpedo provided with my improvements. It will be seen that I provide a water-inlet 25 in the bottom of the air-flask 26, and this inlet is surrounded at its inner end by valve mechanism, such as shown in Fig. 1 and as heretofore described. It is unnecessary, however, with this construction to employ the compartment 2, for the reason that the air-flask ordinarily employed in torpedoes serves every purpose thereof. It will be observed that a shield 13 also extends across the inlet 25 and operates similarly to that hereinbefore described. A valved air-vent 5 is formed in the upper surface of the air-flask to permit the escape of air displaced by water entering the inlet 25. It is of course well known that the air-flask 26 serves to render the torpedo buoyant, and the explosion of the war-head 27 is dependent solely upon the violent contact thereof with a solid object. Under ordinary conditions the torpedo would continue to float upon the water in the event of the failure of its primer to act. Should the torpedo become lost, it will continue to float upon the surface of the water, and there is considerable danger of boats coming accidentally into contact with it and being destroyed. By providing my improvements, such as described in connection with the projectile, the torpedo is caused to sink automatically as soon as its forward movement ceases, for the reason that water will enter above the shield 13 and fill compartment 26, at the same time operating the fuse-igniting mechanism contained within said compartment.

In Fig. 4 I have shown a modified form of

shell to which my improved igniting device has been applied. This shell is not provided with a percussion cap or fuse, but is adapted to be ignited solely by a water-operated primer such as described by me. The shell may be of any desired construction, but preferably has explosive material 28 packed around its compartment 2, and several tubes 22, containing fuses 23, may extend into the explosive from the water-primer.

By reason of the peculiar construction of the valve mechanism the shell or torpedo to which it is applied can be used with absolute safety in a cannon or other like projecting device. Moreover, in lieu of chemical igniting means, such as described, any water-operated mechanical igniting means may be employed.

In the foregoing description I have shown the preferred form of my invention; but I do not limit myself thereto, as I am aware that modifications may be made therein without departing from the spirit or sacrificing the advantages thereof, and I therefore reserve the right to make such changes as fairly fall within the spirit of my invention.

Having thus fully described my invention, what I claim as new, and desire to secure by Letters Patent, is—

30 1. In a device of the class described, the combination with a body formed with an inlet, of means within the body designed to be ignited by contact of moisture, and means for preventing the admission of moisture 35 through said inlet during the longitudinal travel of said body, said means leaving the inlet free for admission of moisture at the conclusion of such longitudinal movement.

2. In a device of the class described, the 40 combination with a body having an inlet, of means within said body designed to be ignited by contact with moisture, pressure-actuated means for admitting moisture through said inlet, and means for maintaining said 45 pressure-actuated means free from the action of surrounding pressure during the longitudinal travel of said body.

3. In a device of the class described, the 50 combination with a body having an inlet and means arranged within said body adapted to be ignited by contact of moisture, of a valve inclosing said inlet, means retaining said valve closed against a predetermined amount of pressure admitted through said inlet, and 55 means for preventing admission of pressure through said inlet during the longitudinal travel of said body.

4. In a device of the class described, the 60 combination with a body, of pressure-energized means arranged within said body, and means for preventing admission of pressure to said body during the longitudinal travel thereof.

5. In a device of the class described, the 65 combination with a body, of moisture-ener-

gized means arranged therein, a valve for preventing admission of surrounding moisture below a predetermined pressure and free to admit such moisture at or above said predetermined pressure, and means for preventing the admission of moisture regardless of the pressure thereof during longitudinal travel of said body.

6. In a device of the class described, the combination with a hollow body, designed to contain an explosive, of moisture igniting means for said explosive, a spherical container for said moisture igniting means, and pressure-controlling means for admitting moisture to said container.

7. A device of the character described, comprising a recessed body having an inlet, an oscillatory shield adapted to be seated within the recess, and means for automatically projecting the shield from the recess to open the inlet.

8. A device of the character described, comprising a recessed body having an inlet, a winged, oscillatory shield mounted within the recess and across the inlet, and means for automatically projecting the shield from the recess.

9. In a device of the character described, a body having a compartment therein, and a normally closed inlet to the compartment, a "water-primer" in the compartment, and pressure-operated means for opening the inlet.

10. A device of the character described, comprising a body having a compartment therein provided with an inlet, and a valved outlet, a centrally-disposed "water-primer" within the compartment, and pressure-operated means for opening the inlet.

11. A device of the character described, comprising a body having a compartment therein, provided with a valved inlet and an outlet, a "water-primer" in the compartment, pressure-operated means for opening the inlet, and a shield for said means.

12. A device of the character described, comprising a body having a compartment therein, provided with a valved outlet and an inlet, a perforated casing within the compartment and extending from the inlet, a pressure-operated, cut-off device within the casing, and a shield across the inlet.

13. A device of the character described, comprising a body having a compartment therein, provided with a valved outlet and an inlet, an apertured casing within the compartment extending from the inlet, a pressure-operated cut-off device within the casing, and an oscillatory shield connected to the body and extending across the inlet.

14. A device of the character described, comprising a body having a compartment therein, provided with a valved outlet and an inlet, a pressure-operated casing within the compartment and extending from the inlet,

a pressure-operated, cut-off device within the casing, and a spring-controlled, oscillatory shield extending across the inlet.

15. A device of the character described, comprising an explosive-containing body having a compartment therein, said compartment being provided with a vent and an inlet, an apertured casing within the compartment and surrounding the inlet, a pressure-operated, cut-off device within the casing, a "water-primer" supported within the compartment, and a fuse extending from the "water-primer."

16. In a device of the character described, the combination with a body having a compartment therein, provided with a normally closed inlet and a vent, of pressure-operated means for automatically opening the inlet, and water-operated igniting means within the compartment.

17. In a device of the character described, the combination with a body having a compartment therein provided with a vent and a normally closed inlet, of pressure-operated means for automatically opening the inlet, means adapted to prevent the admission of water to the inlet during the movement of the body in one direction, and water-operated igniting means within the compartment.

18. A device of the character described, comprising a body having a compartment therein, provided with a vent and a normally closed inlet, pressure-operated means for automatically opening the inlet, an oscillatory shield extending across the inlet and adapted to prevent the admission of water to the inlet, when the body is moving in one direction, and water-operated igniting means within the compartment.

19. A device of the character described, comprising a body having a compartment therein, provided with an inlet, a deflecting device upon the body and extending across the inlet, and water-operated igniting means within the compartment.

20. A device of the character described, comprising a body having a compartment therein, provided with an inlet, an oscillatory deflecting device connected to the body and extending across the inlet, and water-operated igniting means within the compartment.

In testimony whereof I hereunto affix my signature in presence of two witnesses.
